UNITED STATES PATENT OFFICE.

CHARLES E. AVERY, OF TRENTON, NEW JERSEY, ASSIGNOR TO MANHATTAN ELECTRICAL SUPPLY COMPANY, OF NEW YORK, N. Y., A CORPORATION OF NEW JERSEY.

SIGNAL-BOX.

1,194,931.

Specification of Letters Patent. Patented Aug. 15, 1916.

Application filed February 3, 1915. Serial No. 5,942.

To all whom it may concern:

Be it known that I, CHARLES E. AVERY, a citizen of the United States of America, and residing at Trenton, in the county of 5 Mercer and State of New Jersey, have invented a certain new and useful Improvement in Signal-Boxes, of which the following is a specification.

My invention relates to signal boxes and 10 particularly to boxes for transmitting an electric signal, the object of my invention being to improve the construction as a whole and certain features of the mechanism in particular as set forth in the following specification and shown in the accompanying drawings in which—

Figure 1 is a perspective of the box casing, with the cover lid open to show the pull lever for operating the mechanism; Fig. 2 20 is a front elevation of the box; Fig. 3 is a section through the wiring box which forms portion of the casing; Fig. 4 is a perspective of the signal box with the inner cover plate opened to show the break wheel and testing devices; Figs. 5 and 6 are plan views of the 25 coöperating parts of a break wheel; Fig. 7 is a cross section through one of these elements; Fig. 8 is a side elevation of the signal circuit contacts and testing devices; Fig. 9 30 is a plan view of these parts; Fig. 10 is a broken plan of the same in position for testing the operating mechanism without sending a signal; Fig. 11 is a perspective of the testing key; Fig. 12 is a plan of the box 35 with the inner cover plate opened to show the signal operating mechanism; Fig. 13 is a detached perspective of the mechanism parts mounted on spindle 93; Fig. 14 is a side elevation of the stop mechanism to prevent overwinding of the operating spring; Fig. 15 is a side elevation of the operating 40 spring in relation to its detent; Fig. 16 is a plan of the stop plate for halting the break wheel after the signal has been given; Fig. 45 17 is a front elevation of the cam hub shown at the left hand end of Fig. 13; Fig. 18 is a detached perspective of this hub and the stop plate viewed from the opposite direction from that shown in Fig. 13; Fig. 19 50 is a section through the assembled mechanism on the line of the several spindles and showing the signal operating mechanism in a position of rest; Fig. 20 is a broken section showing the mechanism on spindle 93

drawn to a larger scale and in position assumed during the operation of a signaling mechanism; and Fig. 21 is a section on line 21—21, Fig. 19.

The present signal box, while primarily designed to control a circuit in which an electrically operated signal device is arranged, either adjacent or remote from the box, possesses many features which may be utilized in mechanically operated signals. In view of the increasing prevalence of electrically operated signals, especially fire signals, in both factories, school buildings, large office buildings, etc., the invention has been illustrated in connection with mechanism for controlling such an electric signal circuit.

The casing and frame.—The casing may be of any suitable shape, but preferably of generally rectangular form as shown. The body 25 of the casing is a box-like casting having lugs 26 projecting from the bottom 75 for the reception of securing screws and side brackets 27 through which the spindle 28 passes. Pivoted on the latter by lugs 29 is an inner cover plate 30 on the inner face of which the operating mechanism is mounted. This plate is normally locked in closed position by the key operated screw 31 thereon which takes into the tapped boss 32. An outer protective cover 33 is also pivoted on the spindle 28 by lugs 34 and is normally held in closed position by the coil spring 35, one end of which is socketed in a lug 29 of the inner cover plate and the other end in a lug 34 of the outer cover. On the exterior of the outer cover 33 is a suitable instructive legend, and the number of the signal which is rung from the box. This number is preferably impressed on an independent disk 36 held by a rivet 37 in a countersunk seat in the cover. A marginal finger grip 90 38 is provided by which to open the cover when it is desired to operate the signal.

One corner of the box body is preferably cut away to form an independent wiring box 39 which may be installed in advance of 100 the main box containing the signaling mechanisms. Tapped bosses 40 in the opposite ends of this wiring box 39 receive the wire conduits 41. Temporary filler pieces 42 (Fig. 1) may be screwed into these bosses 105 until the conduits are connected, or one of them may be permitted to remain in permanently where the box forms a terminus in

the conduit system. Lugs 43 receive screw bolts by which the wiring box is independently mounted on the wall or other support. The meeting faces of the casing 25 and wiring box 39 lie in a plane at an angle of about 45° to the bottom of the casing, so that it is possible to machine these faces to an exact fit, a practical impossibility where the box 39 is rectangular and there are two meeting faces lying at an angle to one another.

Electrical connections.—Mounted by screws 44 within the wiring box 39 is a block 45 of insulation carrying terminal straps 46-47 with binding screws 48, 49, for the conduit wires. This installation may be completed in advance of the attachment of the main box, in order to save the latter from the dirt and possible injury incident to the completion of the building construction or to the wiring job when the installation is made in a building already completed. When the system is to be made ready for use the boxes 25 are assembled with the wiring boxes 39 by means of screws 50 passing through flanges 51 and taking into tapped holes 52 in the conduit bosses 40. Each terminal strap 46, 47 also carries a binding screw 53, 54, by which, after the boxes 25 and 39 are thus assembled, wires 55 and 56 are respectively attached to the straps 46, 47. These wires lead to a pair of coöperating spring terminals 57 and 58 mounted through insulation on a boss 59 on the inner face of the base 30. The signal circuit which the mechanism controls may be either normally open or normally closed. The more common practice is to employ a circuit normally closed and accordingly the contacts 57 and 58 are here shown in engagement at their free ends.

The break wheel.—To open the circuit and thus to operate the signal, I provide a break wheel 60 rotating in the direction indicated by the arrow 61. This wheel has a series of peripheral teeth 62 which, on the rotation of the wheel, successively engage the free end 63 of the spring terminal 58 and depress it out of engagement with the coöperating terminal 57. The circuit being automatically reestablished by spring contact 58 after each depression, it is obvious that the signal is operated to sound in accordance with the number of teeth on the break wheel. In the example shown the signal rings the number 35, since the first group of three teeth is spaced from the second group of five teeth a longer interval than the space between adjacent teeth thus giving a pause between the two groups, while a still longer pause is permitted between the five group and three group as they succeed each other during the rotation of the break wheel.

The break wheel is ordinarily made from a metallic disk into the periphery of which the teeth 62 are cut or filed in accordance

with the signal number which is desired for the particular box in which the wheel is to be used. This method of making the break wheel is expensive and time-consuming and often results in a considerable delay in the filling of orders. To obviate these disadvantages the present break wheel is built up from a plurality of separate disks 64 provided with peripheral teeth of different numbers. By variously combining these disks practically any series of numbers can be obtained which a given installation may require. In Figs. 5 and 6 I have shown two disks, one having five peripheral teeth and the other three. There may of course be as many teeth as are necessary and their pitch may vary as required. A stock of these may be readily made and kept on hand for building up the desired numbers. By arranging the two disks shown in such manner on their spindle 115 that the disk with three peripheral teeth comes first into engagement with the contact end 63, the box number 35 is sounded on the rotation of the break wheel. Any suitable means may be employed for holding the disks rigid with relation to each other. I have here shown each disk provided on one face with teats 65 which take into corresponding cups 66 on the meeting faces of the adjacent disk. The disks are preferably struck from sheet metal and the teats and cups 65, 66, may be made simultaneously with the cutting of the peripheral teeth 62 by suitable construction of the cutting dies. A nut 600 holds the disk rigid on the spindle 115 through the insulating connection 610.

The testing devices.—It is a common provision of municipal fire regulations that signal boxes employed for the ringing of fire alarms shall be subject to tests to determine not only that the electrical connections are in proper working order but also to determine independently that the signal operating mechanism is in proper working condition. In the latter case it is desired that the mechanism be tested without ringing the signal.

To test the circuit an interrupter 67, independent of the break wheel, is provided which may be operated by a key 68 without opening the inner cover 30 of the box. In the form here shown, this interrupter comprises a plate of insulation 67 freely mounted on a pin 69 cast in one with or carried by the base plate 30. A hole 70 in the plate 67, lying just outside the area of the pin 69, receives the tongue 71 of the key 68. The latter is of partially cylindrical form and may be passed through the arcuate slot 72 in the base plate 30 surrounding the base of the pin 69. It will be noted that the entering end of the key has an arcuate extent substantially as great as that of the slot 72 so that the key may be inserted in only a

single position. The hole 70 in the interrupter 67 is so positioned with relation to the slot 72 that the tongue 71 on the key registers therewith when the key is inserted. 5 The shank of the key is however recessed at 73 to permit the latter to be rotated a predetermined extent after insertion, that is to say, until the base of the recess 73 in the shank of the key comes to bear upon one end 10 of the slot 72 in the base plate. Consequently, the motion which it is possible to give to the interrupter 67 is positively limited by the depth of the recess 73 in the key and the positive stop of the latter at the end 15 of the slot 72 in the base prevents any disarrangement of the interrupter 67 and also prevents injury to the spring 74 by which the latter is returned to normal position against its stop 75. When rotated by the 20 key 68, in the only direction which it is possible to operate the latter after it has been inserted in the slot 72, a nose 670 on the interrupter 67 engages the free end of the spring contact 58 and depresses the latter 25 out of engagement with the coöperating terminal 57. The signal circuit is thus broken and the signal device sounded without operating the break wheel. Thus no box signal is rung and there is no danger of alarm 30 being caused by the single stroke of the signal bell which results from this test breaking of the circuit by the interrupter 67.

It would obviously be impossible to test the break wheel operating mechanism without 35 ringing the box number unless the contact 63 be temporarily moved out of position in which the break wheel would engage it during the rotation thereof on a test of the mechanism. To accomplish this, while 40 at the same time maintaining the circuit closed, a second insulating plate 76 is mounted on a second stud 77 and having an aperture 78 for the reception of the tongue 71 of the key 68. An arcuate slot 79 surrounds 45 the base of this stud in like manner as slot 72 for stud 69, and the tongue 71 on key 68 when the latter is inserted through slot 79, engages in hole 78 so that the plate 76 may be rotated thereby. On rotation by the key 50 the nose 80 on the plate 76 rides on the arched free end of the spring terminal 57 and depresses the latter, carrying down with it the free end 63 of terminal 58 so that the latter lies out of the path of the teeth 62 on 55 the break wheel and at the same time maintaining the circuit closed. In this position the break wheel may be rotated without opening the signal circuit and the test of the mechanism is thus silent. On the release of 60 the key, the spring 81 returns the disk 76 to normal position against its stop 82 while the contacts also resume their normal position. The arcuate motion of the key 68 is in this case also limited by the depth of the 65 recess 73 therein and danger of disarrange-

ment of the plate 76 or of injurious strain upon its spring 81 or the spring terminals 57 and 58 is prevented.

The break wheel operating mechanism.—
In case of fire the signal is rung by a mechanism mounted within the casing and set in motion by the pull lever 83. The latter, which is the only element of the mechanism accessible after the cover base 30 has been locked in position, extends through a slot 84 70 75 in the case and is normally maintained at the top of the slot by its return spring 85.

The spindle 86 to which the lower end of the lever 83 is fast has pinned thereto a collar 87 engaged by one end of the return spring 85 and also a hub 870 provided with a ratchet wheel 89. The gear 88 freely mounted on the hub, carries a pawl 90 pressed by spring 91 into engagement with the ratchet 89, thus receiving its drive 85 through the latter on the downward movement of the lever 83 while permitting the ratchet to run freely beneath the pawl 90 on the upward return movement of the lever under the influence of its spring 85. 90

In mesh with the gear 88 is a pinion 92 pinned to shaft 93 and rigid with a ratchet 94. The latter is provided with as many teeth as may be desired, but having a predetermined relation to the stops 112 on the 95 stop plate 107 hereinafter mentioned. A pawl 95 mounted on the cover plate 30 and pressed by spring 96 into engagement with the ratchet 94 holds the latter against reverse rotation, and consequently holds, 100 through pinion 92, the gear 88 stationary during the return movement of the lever 83 under the influence of its spring 85.

The heavy driving spring 97 coiled on spindle 93 is pinned at its inner end to the latter, while its outer end is wrapped on a pin 98 extending between the plate 99 on the one side and gear 100 on the opposite side. Rigidly supported from the cover plate 30 by pins 101 is an internally toothed ring 110 105 110 102. A pawl 103 pivoted on the hub of pinion 92 and located within the ring is normally held by its leaf spring 104 out of engagement with the toothed inner periphery of the ring 102. A lug 105 (Fig. 14) 115 struck from plate 99 lies however in the path of the pawl 103 and throws the latter outward into engagement with the ring 102 on the rotation of the spindle 93 by the gear 88 beyond a predetermined maximum. 120 Over-winding of the actuating spring 97 is thus prevented.

Adjacent the gear 100 but pressed away therefrom by the spring 106, is a stop plate 107 mounted freely on the shaft 93 but having a lost motion connection with the gear 100 through a pin 108 on the gear wheel taking into a slot 109 in the stop plate. The opposite ends of the spring 106 take into holes 110 and 111 in the gear 100 and stop 130

plate 107 respectively and the torsional effort of the spring is in a direction to rotate the stop plate 107 backward, that is to say in a direction opposite to its direction of travel during the operation of the mechanism. The object of this is to insure the proper stop action thereof, as will be herein-after explained. Radial stop bars 112 on the opposite side of the plate 107 engage in stop position, with a pin 113 on gear 114 fast on the shaft 115 of the break wheel 60, and geared at the ratio of five to one with the main gear 100 through the pinion 121 on the hub of gear 114. Spindle 115 thus makes five revolutions to one revolution of shaft 93. Bearing against the same face of the stop plate at a point radially inside the stop bars 112 is a hub 116 pinned to the spindle 93 and provided with cam projections 117-118 spaced radially different distances from the spindle 93 and which, in the stop position of the mechanism, enter arcuate slots 119 and 120 respectively, also spaced different radial distances from the axis of the stop plate. In this stop position, the stop plate 107 is pressed away from gear 100 by spring 106 and the radial stop bars 112 lie in the plane of rotation of the pin 113 on the gear wheel 114 (Fig. 19) so that one of said stop bars is engaged by said pin. On the rotation of the shaft 93 by the pull down of the lever 83, however, the hub 116, turning with the shaft 93 (and in advance of the locked gears 100 and 114, which are halted by the engagement of pin 113 on the latter with one of the stop bars 112 on stop plate 107) the stop plate is displaced longitudinally on the shaft 93 against the spring 106 by the cam projections 117 and 118 on the hub 116, which projections ride out of the slots 119 and 120 against the face of the plate (Fig. 20). This longitudinal movement of the stop plate on shaft 93 carries stop bar 112 out of the path of the pin 113 and thus frees gear 114 which is now driven by spring 97 through gear 100. It should be pointed out that the length of the slots 119 and 120 is such and the inclination of the cams 117 and 118 so predetermined that the engagement between pin 113 and the stop bar 112 is not broken until the spindle 93 has been rotated at least one fifth of a revolution. This insures the tensioning of the driving spring 97 sufficiently to drive the break wheel spindle 115 through a single revolution. It also insures the engagement of the pawl 95 with the succeeding tooth of the ratchet 94 thus holding the spring 97 tensioned. It should be noted also that the position of this ratchet 94 on the spindle 93 is so predetermined with relation to the hub 116 and stop plate 107 that the stop bar 112 of the latter is not withdrawn from engagement with the pin 113 on gear 114 until just after the pawl 95 has engaged

the succeeding tooth of the ratchet 94. There is consequently no danger that the break wheel spindle 115 will be freed and start to rotate before the spring 97 has been put under and held at sufficient tension to insure at least a single complete revolution of spindle 115 and consequently the ringing of the complete signal at least once.

Inasmuch as the spindle 93 is held stationary during the operation of the signal, 75 the stop plate, rotating with gear 100 through the engagement of pin 108 in the forward end of slot 109; gradually brings its slots 119 and 120 into register with the cams 117 and 118 and is then pushed away 80 from proximity to the gear 100 by the expansion of spring 106 and into stop position where its bars 112 lie in the plane of rotation of the pin 113 on gear 114. The latter, turning at five times the speed of the 85 stop plate, soon picks up one of the bars 112 by its pin 113, and turns the stop plate at increased speed in the direction of its rotation, and against the torsional action of the light spring 106, until halted by pin 108 90 which now bears at the rear end (with respect to the direction of rotation) of the slot 109. The mechanism is thus again locked in position. The break wheel 60 is of course so arranged on the spindle 115 that in this 95 locked condition of the operating mechanism the break teeth are positioned to operate the signal device, (i. e. break the circuit) in proper sequence when the mechanism is again set in motion.

In order to time the speed of the signal properly the gear 114 is meshed with a pinion 122 on the hub of gear 123 which engages a verge 124 on spindle 125. The latter carries an oscillating regulator 126, the weighted arms 127 of which may be adjusted on pivot 128 closer to or farther from the axis 125 to speed up or retard the oscillation of the verge which thus forms a governor for the mechanism. A second regulator, 11 if needed, may be mounted on the hub 129 which is tapped at 130 for this purpose.

Operation.—The operation of the break wheel mechanism will be readily understood from the foregoing description. Upon the 11 pull down of the lever 83 the spindle 93 is rotated through the gear 88 and pinion 92. The relation of the gears is such, in the constructions illustrated, that upon a complete stroke of the lever 83 the spindle 93 is rotated slightly in excess of four-fifths of a single revolution. It consequently passes four teeth of the ratchet 94 beneath the pawl 95. The hub 116 on spindle 93 is rotated with the latter through four fifths of 12 a revolution and the cams 117 and 118 thereon passing out of slots 119 and 120 in the stop plate travel around the face of the latter practically to the opposite edges of these slots. The rise of the cams out of the 13

slots forces the stop plate longitudinally of the spindle against the action of spring 106 and the engagement between pin 113 on gear 114 and the stop bar 112 on plate 107 is broken thus permitting the mechanism to operate. Simultaneously with the escape of the pin from the bar 112, the stop plate 107 is rotated backward to the extent of slot 109 by the torsional action of spring 106. The gear 100 is now driven by the main spring 97. Its relation to pinion 121 is as five to one. Consequently on the rotation of the gear 100 through four fifths of a revolution, the spindle 115 will be rotated four times and the signal thus repeated four times by the break wheel 60 thereon. Obviously the pin 113 on gear 114 cannot engage any of the bars 112 on the stop plate 107 during the first three revolutions since they are held out of the path of revolution by the cam lugs 117 and 118 which during this interval are bearing against the face of the stop plate. As the fourth revolution of spindle 115 begins however, the slots 119 and 120 on the stop plate come opposite the cams 117 and 118 on hub 116 and under the pressure of spring 106 the stop plate 107 is forced gradually to the left as the cams enter the slots, and the bars 112 are thus brought into the plane of rotation of the pin 113 on gear 114. As the latter completes its fourth revolution therefore, the pin 113 thereon picks up one of the bars 112 and moves the stop plate ahead (in the direction of its rotation) against the action of spring 106 until halted by the impingement of the end of slot 109 against pin 108. The mechanism is then again locked. While the lever 83 is normally pulled down its full stroke and the mechanism operated as described, it may happen that the lever is pulled down less than a full stroke, say a half stroke. This rotates the ratchet 94 two teeth past the pawl 95, and the hub 116 two-fifths of the way around the stop plate 107. The latter will be displaced by the cams and free the pin 113 so that the mechanism is free to operate; but the stop plate has now only a fifth of a revolution to turn before the slots 118-119 begin to register with the cams 116-117 and it will be displaced by spring 106 into engaging position by the time pin 113 comes around on its second revolution. Should the operator pull the lever down less than sufficient distance to move a tooth of the ratchet 94 past the pawl 95 the signal mechanism will not be operated, since as above explained, the mechanism is so timed that pawl 95 drops against another tooth a moment before the pin 113 escapes stop plate bar 112. Consequently all the parts return to normal position on the release of the lever. Should the operator pull the lever a full stroke and then attempt to pull again, the lever would be halted at once by the stop

pawl 103 which strikes against the pin 105 on the disk 99 and is thrown outward into engagement with the toothed inner periphery of ring 102 before pawl 95 has overrun another tooth of ratchet 94. This also halts the hub 116 before its cams 117 and 118 reach slots 119 and 120 in stop plate 107 and thus prevents their entry into the latter, an occurrence which would result not only in the immediate halting of the mechanism but also in the permanent overtensioning of the spring 97. The latter is obvious since the cams can rise out of the slots only in that direction of rotation which places the spring 97 under tension and they enter the slots again as soon as overtaken by the stop plate when the latter is driven by the spring 97. Of course, after the spring has partially unwound, it is possible by operating the pull lever, to again tension it to the full extent permitted by the stop pawl 103 and pin 105. But the latter again serve to halt the lever before the spring has been overtensioned or the cams 117-118 enter the slots 119-120. It will be noted that while the mechanism will not operate until the lever has pulled the ratchet 94 at least one tooth past the pawl 95, and the pin 113 escaped the stop plate 107, there is then no way in which the proper operation of the signal can be interfered with. At least one complete signal will be properly given. If the lever is pulled farther it merely further tensions the spring (without in the meantime stopping the mechanism) and sets the stop mechanism in position to operate later. Moreover, it is not necessary to release the lever to free the mechanism. Once the pin 113 has escaped the stop plate 107, the signal is given however the lever is thereafter operated and whether it is released or not.

The lost motion engagement between the gear 100 and stop plate 107 through pin 108 permits the spring 106 to reversely rotate the stop plate in order to bring the proper stop bar into position to be engaged with certainty by the pin 113. This provision is practically of considerable importance since otherwise the positioning of the engaging parts must be determined with such exactitude and the construction of the meeting faces made with such fineness as to be impossible from a manufacturing standpoint since the reengagement of the stop pin 113 with the stop bar 112 would have to take place at precisely the exact point of release. By rotating the stop plate backward slightly, after the escape of the pin 113, the reengagement between the pin and bar takes place in advance of the exact stop position, while the latter is still accurately determined by the stop end of the slot 109 meeting the pin 108 on gear 100.

Variations in the details of construction will readily suggest themselves to those

skilled in the art and the mechanism shown is to be regarded merely as an illustrative embodiment of what I claim as my invention.

5. I claim as my invention:—

1. Means for providing a built-up operating rotor for a single signal-contact couple, comprising a plurality of operating units, each having a different number of peripheral teeth, said teeth being of similar form and spacing for each unit, in combination with means for securing a plurality of said units together in such relation that the desired number of teeth for the signal are arranged to operate in sequence upon the contact couple.

2. Means for providing a built-up operating rotor for a single signal-contact couple, comprising a plurality of operating units, each having a different number of peripheral teeth, said teeth being of similar form and spacing for each unit, in combination with means for securing a plurality of said units together in such relation that the desired number of teeth for the signal are arranged to operate in sequence and in spaced groups upon the contact couple.

3. Means for providing a built-up operating rotor for a single signal-contact couple, comprising a plurality of operating units, each having a different number of peripheral teeth, said teeth being of similar form and spacing for each unit, in combination with means for securing a plurality of said units together in such relation that the desired number of teeth for the signal are arranged to operate in sequence upon the contact couple, said means comprising interlocking teats and cups on the juxtaposed faces of the operating units.

4. A signaling device having a built-up operating rotor for a single signal-contact couple, said rotor comprising a plurality of operating units each unit being provided with a single group of peripheral teeth of similar form and spacing, said units being secured together in such relation that the teeth on the respective units operate in sequence upon the contact couple to effect the desired signal number.

5. A signaling device having a built-up operating rotor for a single signal-contact couple, said rotor comprising a plurality of operating units each unit being provided with a single group of peripheral teeth of similar form and spacing, said units being secured together in such relation that the groups of peripheral teeth are spaced apart circumferentially to operate at spaced intervals upon the contact couple whereby a desired signal number comprising a plurality of digits is effected.

6. A signal device having a built-up operating rotor for a single signal-contact couple, said rotor comprising a plurality of

imperforate sheet metal units struck to shape, each unit having a single group of peripheral teeth of similar form and spacing and having teats and cups on its opposite faces to coöperate with like elements of a juxtaposed unit whereby the units are held against relative rotary displacement in assembled position, said teats and cups having a predetermined relation to the peripheral teeth to insure lateral interlock between juxtaposed units in various relative circumferential positions of the peripheral teeth groups.

7. An electric signaling device comprising a pair of spring contacts in the signal circuit, an operating wheel for intermittently displacing one of said contacts to operate the signal circuit, in combination with means independent of said wheel for displacing said contact to operate said signal circuit to test the same.

8. An electric signaling device comprising a pair of spring contacts in the signal circuit, an operating wheel and means for rotating the same to intermittently displace one of said contacts to operate the signal circuit, in combination with means independent of said wheel for displacing said contact out of the path of said wheel while maintaining the signal circuit in its original condition whereby the wheel rotating means may be silently tested.

9. An electric signaling device comprising a box-like casing, a pair of spring contacts mounted within said casing and arranged in the signal circuit, an operating wheel for intermittently engaging one of said contacts and mechanism within the casing for rotating said wheel, in combination with key controlled means operable from the exterior of said casing for displacing said contact to operate the signal circuit.

10. An electric signaling device comprising a contact device in the signal circuit, an operating wheel for intermittently engaging said contact device to operate the signal circuit, in combination with means independent of said wheel for engaging said contact device to operate the signal circuit to test the same.

11. An electric signaling device comprising a pair of normally closed contacts in the signal circuit, a rotatable break wheel adapted to intermittently engage and displace one of said contacts to open the signal circuit, a plate of insulation adjacent said contact and detachable key means for moving said plate into engagement with said contact to displace the same and thereby open the signal circuit independently of the break wheel.

12. An electric signaling device comprising a box-like casing, a pair of normally closed contacts in the signal circuit mounted within said casing, a break wheel adapt-

ed to intermittently engage and displace one of said contacts to open the signal circuit, a plate of insulation mounted adjacent said contact and apertured to receive an actuating key, a key way in the casing and a detachable key adapted to be passed through said key way in the casing and having a lug to engage said aperture in the said plate to move the latter into engagement 5 with said contact and displace the latter and open the signal circuit.

13. An electric signaling device comprising a box-like casing, a pair of normally closed contacts mounted within the latter 15 and arranged in the signal circuit, a plate of insulation pivotally mounted adjacent said contacts and apertured to receive a key, an arcuate key way in the casing and an arcuate key insertible through said key way 20 into engagement with said plate and rotatable in said key way to move said plate into engagement with one of said contacts to displace the same and thus open the signal circuit.

25 14. An electric signaling device comprising a box-like casing, a pair of normally closed contacts mounted within the latter and arranged in the signal circuit, a plate of insulation pivotally mounted adjacent 30 said contacts and apertured to receive a key, an arcuate key way in the casing and an arcuate key insertible through said key way into engagement with said plate and rotatable in said key way to move said plate 35 into engagement with one of said contacts to displace the same and thus open the signal circuit, said key having an arcuate extent at its entering end substantially co-extensive with the key way in the casing 40 and having in its shank a marginal bay limiting, by its depth, the extent to which the key may be rotated in the key way.

15. An electric signaling device comprising, a pair of normally closed spring contacts in the signal circuit, a break wheel 45 adapted to intermittently engage and displace one of said contacts to open the signal circuit, a plate of insulation mounted adjacent the coöperating contact and means 50 to move said plate into engagement with the latter to displace both contacts out of the path of the break wheel.

55 16. An electric signaling device comprising a pair of superposed spring contacts in the signal circuit, and a break wheel having teeth adapted, on the rotation of the wheel, to intermittently depress the lower contact out of engagement with the coöperating contact, in combination with means 60 independent of the break wheel for depressing said lower contact to open the circuit to test the latter.

65 17. An electric signaling device comprising a pair of superposed spring contacts in the signal circuit, and a break wheel hav-

ing teeth adapted, on the rotation of the wheel, to intermittently depress the lower contact out of engagement with the coöperating contact, in combination with means for depressing the upper contact to move 70 the lower contact out of the path of travel of the teeth on the break wheel on the rotation of the latter, whereby the signal circuit may be maintained unbroken during the rotation of the break wheel. 75

18. In an electric signaling device, a pair of spring contacts in the signal circuit, a break wheel for separating the contacts to open the circuit, a pivoted insulating plate movable into engagement with one of said 80 contacts, a casing inclosing said contacts and plate and key means passing through said casing into engagement with said plate and serving to move the latter into displacing engagement with said contact. 85

19. In a signaling device, a rotary signal-operating member, a spring-driven mechanism for rotating said member, and a tensioning lever therefor, said mechanism comprising a winding spindle to which the end 90 of the driving spring is fastened, an operative connection between said spindle and the tensioning lever, a stationary stop member, a pawl rotating with the winding spindle and means for throwing said pawl into 95 engagement with said stop member after the driving spring has reached predetermined tension.

20. In a signaling device, a rotary signal-operating member, a spring-driven mechanism for rotating said member, and a tensioning lever therefor, said mechanism comprising a winding spindle to which the end 100 of the driving spring is fastened, a pinion fast on said spindle and operatively connected to the tensioning lever, a pawl pivoted on said pinion, a stationary internally toothed ring surrounding said pawl, and means for throwing said pawl into engagement with the stop member after the driving 105 spring has reached predetermined tension. 110

21. In a signaling device, a driving spring, a winding spindle fast to the inner end of said spring, a stop ring serrated on 115 its inner periphery, a pawl rotating with said winding spindle in the plane of said stop ring, and a member driven by said spring and having a projection adapted to engage said pawl to throw it into engagement with the stop ring and thereby halt 120 the winding spindle.

22. In a signaling device, a driving spring, a winding spindle fast to the inner end of said spring, a stop ring serrated on 125 its inner periphery, a pawl rotating with said winding spindle in the plane of said stop ring, and a member driven by said spring and having a projection adapted to engage said pawl to throw it into engage- 130

- ment with the stop ring and thereby halt the winding spindle, together with means to maintain said pawl normally out of engagement with the stop ring.
- 5 23. In a signaling device, a rotary signal-operating member, a driving spring therefor, and an escapement mechanism controlling the operation of said driving spring, said mechanism comprising a member driven 10 by the spring, a stop plate having a lost motion connection therewith in the direction of rotation and a driving element for the signal-operating member having means to temporarily engage said stop plate.
- 15 24. In a signaling device, a rotary signal-operating member, a driving spring therefor, and an escapement mechanism controlling the operation of said driving spring, said mechanism comprising a member driven 20 by the spring, a stop plate having a lost motion connection therewith in the direction of rotation and a driving element for the signal-operating member having means to temporarily engage said stop plate, together 25 with means to move said stop plate out of detaining position.
25. In a signaling device, a rotary signal-operating member, a driving spring therefor, and an escapement mechanism controlling 30 the operation of said driving spring, said mechanism comprising a member driven by the spring, a stop plate having a lost motion connection therewith in the direction of rotation and a driving element for the 35 signal-operating member having means to temporarily engage said stop plate, together with cam means to move said stop plate out of detaining position.
26. In a signaling device, a rotary signal-operating member, a driving spring therefor and an escapement mechanism controlling 40 the operation of said driving spring, said mechanism comprising coöperating gears driven by said spring, a rotary stop plate having a lost motion connection and moving with one of said gears and a detent on the other gear adapted to temporarily 45 engage and be detained by said stop plate.
27. In a signaling device, a rotary signal-operating member, a driving spring therefor, a pair of gears in the driving connection, and an escapement device for the same, comprising a rotary stop plate connected with lost motion to and moving with one of 50 said gears, a detent on the other of said gears to temporarily engage said stop plate, means to wind said spring and means to displace said stop plate out of detaining position after the spring has been tensioned to a 55 predetermined extent.
28. In a signaling device, a rotary signal-operating member, a driving spring there- 60
- for, a winding spindle for said spring, a gear mounted on said spindle and driven from said spring, a stop plate mounted adjacent said gear, a spring normally pressing said plate away from said gear, a cam on the spindle for displacing said plate toward said gear in opposition to the action of said spring, and a member in the driving connection engaging said stop plate when in normal position to halt the mechanism.
29. In a signaling device, a driving mechanism comprising a driving spring, a gear driven thereby, a stop plate having an escapement connection with said gear and means for establishing reengagement between said plate and gear at a point in advance of the point of escapement.
30. In a signaling device, a driving mechanism comprising a driving spring, a gear driven thereby, a stop plate having limited freedom of oscillation, means for displacing said plate out of engaging position and means for oscillating said plate, thus freed, to such position that the reengagement between the same and said gear will occur at a point in advance of the stop position.
31. In a signaling device, a pair of electrical contacts in the signal circuit, a rotary member for operating the same, an operating mechanism, a box-like casing inclosing said parts, said box being open at one corner, an independent box adapted to receive wire conduits, an insulating base carried thereby and having terminals thereon for the line wires of the signal circuit, and independent terminals for connection to the contacts within the main box, together with means to secure said main and corner boxes in assembled condition.
32. In a signaling device, a pair of electrical contacts in the signal circuit, a rotary member for operating the same, an operating mechanism, a box-like casing inclosing 90 said parts, said box being open at one corner, an independent box adapted to receive wire conduits, an insulating base carried thereby and having terminals thereon for the line wires of the signal circuit, and independent 95 terminals for connection to the contacts within the main box, together with means to secure said main and corner boxes in assembled condition, the meeting faces of said boxes being inclined to the base thereof and 100 lying in a plane.
- In testimony whereof I have signed my name to this specification, in the presence of two subscribing witnesses.
- CHARLES E. AVERY.
